(57) **CLAIM**

The ornamental design for a high-density optical module system, as shown and described.

DESCRIPTION

FIG. 1 is a top, front and right side perspective view of a high-density optical module system embodying our new design;

FIG. 2 is an enlarged partial top perspective view thereof; FIG. 3 is an enlarged partial left side cross-sectional view thereof, showing a partial side view of optical module connectors;

FIG. 4 is a side cross-sectional view of a high-density optical module system without cables showing a top sliding cassette extended, the opposite side view being a mirror image thereof;

FIG. 5 is another side cross-sectional view thereof with the top sliding cassette fully inserted, the opposite side view being a mirror image thereof; and,

FIG. 6 is another side cross-sectional view thereof with a local cross section showing a partial side view of the connectors, the opposite side view being a mirror image thereof.
